UNITED STATES PATENT OFFICE.

JOHN W. TEETZEL, OF URBANA, ILLINOIS.

WELL-DRILLING MACHINE.

No. 888,205.

Specification of Letters Patent.

Patented May 19, 1908.

Application filed March 22, 1907. Serial No. 363,898.

To all whom it may concern:

Be it known that I, JOHN W. TEETZEL, a citizen of the United States, residing at Urbana, in the county of Champaign and State of Illinois, have invented certain new and useful Improvements in Well-Drilling Machines, of which the following is a specification.

This invention relates to well drilling machines.

One object is to provide a comparatively simple, inexpensive, durable and efficient machine of the character stated.

Another object of the invention resides in the provision of a machine embodying such features that the drill may be driven characteristic of the trip hammer principle as distinguished from those machines wherein the drill is raised and permitted by its own weight and the impact to cut and bore, whereby the drilling of the well may be more expeditiously accomplished.

A still further object of the invention is to so construct the drill and coöperating parts that the former may serve in the capacity of a pump for flushing purposes to carry off the debris by a continuously maintained flow of water without the use of auxiliary forcing means, such as an extra pump.

It is still further designed to embody in a drilling machine the necessary strength, compactness, very little friction, positiveness with respect to movement, a maximum of speed and a free turn of the tools, without the employment of belts, pulleys, chains, sprocket wheels, ropes and sheaves, cones, ratchets, levers, etc., which latter form a prominent part in nearly all of the drilling machines now upon the market.

With the above and other objects in view, the present invention consists in the combination and arrangement of parts hereinafter described, illustrated in the accompanying drawings and particularly pointed out in the appended claims, it being understood that changes may be made in the form, size, proportion and minor details without departing from the spirit or sacrificing any of the advantages thereof.

In the drawings:—Figure 1 is a side elevation of my improved invention. Fig. 2 is a plan view of the walking beam. Fig. 3 is a horizontal sectional view of the machine below the walking beam. Fig. 4 is a front elevation, parts being broken away. Fig. 5 is a

perspective view of a portion of the machine illustrating particularly the sectional front pipe connections mounted upon suitable supporting rails. Fig. 6 is a sectional view of the lower end of the drill rod and drill. Fig. 7 is a detail fragmentary view of the temper screw and certain of its coöperating elements. Fig. 8 is a detail view of a wedging member designed to assist in wedging the temper screw into engagement with the drill rod sections or for the connecting together of the sections composing the drill rods. Fig. 9 is a detail fragmentary view of the cross head, showing the collar embracing two part nut and strapped to the cross head to prevent said nut from rotating.

Referring now more particularly to the accompanying drawings, wherein it will be seen that my machine is preferably of the wheeled type, the reference character 1 indicates the side sills of the bed of the machine connected at their front and rear by the cross beams 2 and 3.

Mounted upon the cross beams are front and rear pairs of uprights 4 and 5 respectively, the front uprights being nearer together than the rear uprights and forming supports for the lower portion 11 of a derrick mast and the forward uprights 4—4 are braced by the brace connections 6 and the rear uprights 5—5 by the brace connections 7. The rear uprights are connected at their upper ends by a beam 8, while the upper ends of the front uprights are connected by a casting 9 to which latter the mast 11 is hinged as 12, whereby the mast may be folded down upon the machine when transporting the latter from one place to another.

Secured in the top of the rear upper cross beam 8 is a pair of eyes 13 designed to pivotally or hingedly receive the U-shaped hinge bolts 14 of the sides 15 of the walking beam whose sides converge toward and embrace the front uprights 4, extending slightly beyond the latter as shown. Each side member 15 of the walking beam has a bearing 16 at its forward end and depending from its under face for the reception of the trunnions 17 of one part 18 of the head connecting the side members at their forward ends, the part 18 having a coöperating similar part 19, hingedly connected thereto, as at 20, with its free end bifurcated to form spaced perforated ears 21, designed to embrace the perforated ear 22 of the part 18 whereby the parts of said head 110

may be locked together by passing a suitable key 23 through said perforation. Each part 18 and 19 is enlarged intermediate its end and provided with a semi-annular recess 25 adapted to embrace the two part nut 26 provided each upon its inner face with screw threads adapted to coöperate with the threads of the hollow temper screw 27 hereinafter more particularly referred to. These parts of the nut, 10 just alluded to, each have upper and lower flanges 28 and 29, respectively, to engage the upper and lower edges of the parts of the front cross head of the walking beam and are permitted to turn freely in the latter whereby 15 the temper screw 27 may be turned in either direction, the nut turning with the screw without raising and lowering the latter. When it is desired to raise or lower the tempering screw 27 for the purpose hereinafter 20 explained, the collar 28^a upon the screw may be moved to embrace the lower end of the said two-part nut and held in engagement therewith by any suitable key 29, with a strap or other suitable means 30 engaging the 25 collar and cross head to compel a raising and lowering of the screw by preventing the rotatable nut from turning in its cross-head. The screw operating handle 30^a may then be grasped and the screw raised or lowered as 30 may be desired.

Connecting the side members 15 of the walking beam are forward and rearward cross bars 31 and 32, respectively, and these cross bars are connected by a slotted supporting 35 bar 33, the slot of the bar 33 having a series of bores 33^a and being designed to receive the upper end of the pitman 34 whose lower end is eccentrically mounted upon the driving shaft 35 journaled in any suitable manner 40 upon the side sills 1 of the frame of the machine, the upper end of said pitman being pivoted by a suitable pin 36 disposed interchangeably in the aforesaid bores 33^a of the supporting bar 33, whereby the upper end of the pitman may be adjusted toward or away 45 from the forward end of the walking beam to increase or decrease the distance of its stroke or vibration.

To overcome unnecessary jarring of the 50 walking beam incident to the operation of the machine, I provide a buffer or cushioning construction which may consist of a transverse supporting bar 37 disposed beneath the walking beam intermediate the ends of the latter, and slidably disposed for vertical movement between the vertical pairs of guides 38 secured in any suitable manner to the side sills 1 and braced by the aforesaid bracing connection 7, there being a second 55 transverse cross bar 39 fixed between the uprights 38 for the support of the helical or other springs 40, upon which latter rests the aforesaid transverse walking beam supporting bar 37.

65 The tempering screw 27 is secured to the

hollow drill rod section 41 by the wedge devices 42 adapted to embrace said drill rod section and fit in the inverted conical shaped cups 43 fixedly carried at both ends of the tempering screw 27. These wedge devices form substantially cone shaped members when arranged about the drill rod and preferably have their inner faces screw threaded, serrated, corrugated or otherwise roughened so that they may firmly grip said drill rod section and prevent disconnection of the latter from the screw when both are raised and lowered. There may be any number of these hollow drill rod sections coupled together depending upon the depth of the well 75 to be bored, another section being added after each section has pierced the earth to the extent of its length, the temper screw having a bore of sufficient diameter to clear the couplings of the drill rod as sections are 80 added, and the temper screw is raised upon the rod for another operation, after having reached the limit of its downward feed. The upper end of the drill rod is swiveled at 45 in the elbow section 46 of the slush pipe, made up of telescoping sections 47, 48 and 49, the swivel allowing the drill rod to turn with relation to the slush pipe which only has a vertical movement. These telescoping slush pipe sections are slidably supported between 85 the guide rails 50 secured to the mast 10 by the pairs of links 51 through the instrumentality of the slidable nuts 52. The upper slush pipe spout will vibrate with the drill rod and telescope into the larger slush pipe 90 48, which latter remains stationary until the drill rod has been fed down into the earth the length of the temper screw, at which period the upper end of slush pipe 47 is on a level with the upper end of slush pipe 48. The 95 slush pipe 48 is now telescoped into the pipe 49 which allows the pipe 47 to move within the two as the drill rod gradually shortens by being driven into the earth. If a new section of drill rod is added the slush 100 pipes are again extended and the swivel connected to the end of new sections, as shown in Fig. 5. The lowermost slush section 49 leads to a tank 53 having communications with the well 54 by way of a suitable pipe 105 connection 55.

Mounted upon the driving shaft 35 is a friction clutch 56 and by operating the clutch in one direction, the driving shaft may be revolved through the instrumentality of a 110 driving pulley 57, to operate the walking beam through the instrumentality of the pitman connection 34 at any desired speed, say for instance, one hundred and twenty-five vibrations per minute, the operator turning 115 the drill rod and lowering the same gradually by turning the temper screw, for which latter operation the aforesaid operating handle 30^a is provided. The motion for operating the various moving parts of the apparatus is ap- 120 125 130

plied in any suitable manner to driving pulley 57. The drill or cutting tool end 58 of the lower drill rod section is hollow to permit the water to enter the drill rod, the water carrying with it the sand, mud, rock etc., loosened by the drill, forcing the water and debris into the drill rod and delivering the same to the slush pipe, the sand, and rock precipitating into the bottom of the tank 53, and the water returning through the overflow pipe 55 to the wall, whereby the water is used over and over again. The cutting end of the drill rod is provided with a ball valve 59 designed to prevent back flow of water and debris. The down stroke of the drill acts in the same manner as a pump, and the rapidity of operation causes a steady stream of water and the drilling products to be lifted up through the drill rod and the water returned to the well in the manner stated.

As shown in Fig. 3 the friction wheel 60 is normally out of engagement with the friction pulley 61, and is brought into frictional contact with the pulley 61, only when it is desired to use the winding drum 62 or the cat head 63, to wind or unwind a rope 64 which is passed over the pulleys 65 of the mast head 66 and attached to the temper screw, drill rod, or slush pipe sections, to elevate or lower the same, or for suspending such parts until the required connections are made therebetween, or new sections are added to the well casing or drill rod. The winding drum 62 is slidably mounted upon the shaft 66 upon which the friction wheel 60 is also mounted, and at one end it has a number of locking projections 67 designed to engage the corresponding recesses 68 on the inner side of the friction wheel 60. A friction brake 69 engages one end of the drum and is controlled by a lever 70 connecting the brake by the link 71. This brake is applied when the drum is free of the friction wheel 60, so that the speed of the same may be controlled as the rope is unwound, and the drum 62 is shifted laterally into locking engagement with the friction wheel 60 through the instrumentality of a suitable lever 72 pivoted intermediate its ends in the bearing 73 secured to the frame.

The driving shaft 35 is provided with a suitable balance wheel 74, and the winding drum shaft 66 has an eccentric bearing 75 operated by the lever 76 having connection with the bearing blocks of the eccentric bearing through the instrumentality of the link 77. One end of the shaft 66 is mounted to have a little play while its opposite end is journaled in an eccentric bearing, as shown in Fig. 1. The friction pulley 60 is brought into engagement with the drive friction by shifting the eccentric bearing 75 in which one end of the shaft 66 is mounted, as just stated.

65 It is necessary to move this shaft 66 by the

eccentric mounting but a fraction of an inch to bring the friction pulley 60 in or out of engagement with the driving friction pulley 61.

From the foregoing it will be understood that as the driving shaft 35 is driven it causes a rapid up and down movement of the walking beam through the instrumentality of the pitman 34, the jarring occasioned by the reciprocation of the walking beam being overcome through the instrumentality of the springs 40. This rapid reciprocation or vibration of the walking beam causes a rapid up and down movement of the drill rod whose lower end cuts into the earth to loosen the soil and rocks, and by its impact forces the water up the tubular drill rod carrying with it the dirt, rocks, and other foreign matter and thence down the slush pipe toward the well, the dirt and rocks being separated by the water by precipitation into a tank with a return of the water to the well to be used over and over during the operation of the machine. It will also be understood that while the machine is running the tempering screw is gradually worked downwardly, giving a positive and powerful feed incident to the striking of a terrible blow.

It will be understood that the slush pipe sections may be added as required and that the drill bores its own way. It will also be understood that after the drill is in operation, the operator feeds down the drill by turning the temper screw say one-half inch. The result is that the drill can only penetrate the ground one-half inch. However, the drill works so rapidly that the feed may be practically continuous, so that the same will penetrate say one-fourth inch at each down stroke. The feed will be varied by the operator according to the nature of the soil. When boring through rock the drill would be fed very slowly. It will also be understood that I may test a well without the use of a separate pump.

What is claimed is:—

1. In a well driving machine, a wheeled body, a mast, a walking beam pivoted at one end to said body and embracing the mast, a hollow drill rod connected to one end of the walking beam, a tempering screw disposed in the line of the drill rod, a slush pipe communicating with the drill rod, a driving shaft, and a pitman connection between the driving shaft and walking beam to operate the latter and reciprocate the drill rod.

2. In a well drilling machine, a wheeled body, a mast, a walking beam pivoted at one end to said body and embracing the mast, a hollow drill rod connected to one end of the walking beam, a slush pipe communicating with the drill rod, a driving shaft, and connecting means between the driving shaft and walking beam to operate the latter and reciprocate the drill rod.

3. A well drilling machine comprising a

- frame, a walking beam pivotally mounted upon the frame, a sectional hollow drill rod having connection with the walking beam, means connected to the drill rod whereby the 5 same may be raised and lowered independently of the movement of the walking beam, a slush pipe communicating with the drill rod, and means for operating the walking beam.
10. 4. A well drilling machine comprising a bed frame, a walking beam pivotally mounted at one end upon said frame, a drill rod having connection with the free end of the walking beam, means for operating the walking beam, spaced vertical members connected to said frame, a transverse member connected to said beam and with its ends movably disposed between said vertical members, and cushion springs bearing beneath said 15 transverse member.
15. 5. A well drilling machine comprising a frame, a walking beam pivotally mounted at one end upon the frame and comprising spaced side members and spaced intermediate transverse members, longitudinal members spaced apart and connecting said transverse members and provided with a plurality of transverse spaced apertures, a drive shaft, a pitman connected at one end to the drive 20 shaft, means for connecting the other end of the pitman adjustably to said apertures, a drill rod having connection with the outer end of the walking beam, and means for raising and lowering the drill rod independently 25 of the movement of the walking beam.
30. 6. A well drilling machine comprising a frame, a walking beam mounted upon the frame, a driving shaft, a connection between the driving shaft and walking beam to operate the latter, a hollow drilling rod having connection with the walking beam, a slush pipe having communication with the drill rods, and means for rotating the driving shaft to operate the walking beam and reciprocate the drilling rod.
35. 7. In a well drilling machine, a frame, a walking beam mounted upon the frame, a driving shaft, a pitman connection between the driving shaft and walking beam to operate the latter, a drill rod made up of hollow sections and having connections with the walking beam, a slush pipe made up of telescoping sections communicating with the drill rod, and means for rotating the driving shaft.
40. 8. In a well drilling machine, a frame, a walking beam pivotally mounted upon the frame, a driving shaft, a connection between the driving shaft and walking beam to operate the latter, a mast, hollow drill rod sections having connection with the walking beam, slush pipe sections telescoping with one another having communication with the drill rod sections, means for supporting the slush pipe sections upon the 45 mast, and means for driving the driving shaft.
50. 9. In a well drilling apparatus, a frame, a walking beam, a driving shaft, an eccentric connection between the driving shaft and walking beam, a two part head carried at one end of the walking beam, a rotatable nut mounted in the two-part head, a hollow tempering screw mounted in the nut of said head, hollow drill rod sections for connection with the tempering screw, slush pipe telescoping sections having communication with the drill rod sections and the tempering screw, means for operating the tempering screw and drill rod sections independently of the walking beam, and means for holding 55 said nut against rotation.
55. 10. In a drilling machine, a frame, a walking beam pivotally mounted upon the frame, a driving shaft, a pitman connection between the driving shaft and walking beam, means for cushioning the walking beam, a mast, a walking beam comprising converging side members embracing the mast, a hollow tempering screw having detachable connection with the walking beam, hollow drill rod sections detachably connected to the tempering screw, the lowermost drill rod section carrying a valve, a plurality of slush pipe sections telescopically united with one end section and communicating with the drill rod and tempering screw, guiding rails carried by the mast for the support of the slush pipe sections, means coöperating with the lowermost slush pipe section to separate the sediment from the water, and means coöperating with the last mentioned means to return the water to the well.
60. 11. In a drilling machine, a frame, a walking beam pivotally mounted upon the frame, a driving shaft, a pitman connection between the driving shaft and walking beam, means for cushioning the walking beam, a mast, a walking beam comprising converging side members embracing the mast, a hollow tempering screw having detachable connection with the walking beam, hollow drill rod sections detachably connected to the tempering screw, the lowermost drill rod section carrying a valve, a plurality of slush pipe sections telescopically united with one end section communicating with the drill rod and tempering screw, guiding rails carried by the mast for the support of the slush pipe sections, means coöperating with the lowermost slush pipe section to separate the sediment from the water, means coöperating with the last mentioned means to return the water to the well, and means for raising and lowering the tempering screw and drill rod independently of the walking beam.
65. 12. In a well drilling machine, a wheeled frame, a driving shaft mounted in the frame, a walking beam, including converging side

members and an intermediate longitudinal member having spaced transverse apertures, a pitman having connection at one end with the driving shaft and adjustable connection at the other end with the apertures of the longitudinal member of the walking beam, means for cushioning the walking beam, and means having connection with the walking beam for drilling the well.

10 13. In a well drilling machine, a frame, a drive shaft mounted upon the frame, a walking beam pivoted at one end to the frame, a pitman having connection with the drive shaft and adjustable connection with the walking beam, a mast, a head carried by said mast and provided with spaced cable guide pulleys, well drilling elements comprising a hollow drill rod, means for coupling said drill

rod to the free end of the walking beam, and a plurality of slush pipe sections telescopically united with one end section communicating with the drill rod, a second shaft mounted in the frame, a winding means carried by the second shaft, and a cable connected with said winding means and passing over said guide pulleys and connected with the well drilling elements to raise and lower the same.

15 In testimony whereof I have signed my name to this specification in the presence of two subscribing witnesses.
